UNITED STATES PATENT OFFICE

2,596,331

SEVERABLE MULTIPLE UNIT CASE

Kenneth C. Ferguson, Indianapolis, Ind., assignor
to Inland Container Corporation, Indianapolis,
Ind., a corporation

Application March 9, 1950, Serial No. 148,634

4 Claims. (Cl. 229—27)

1

This invention relates to a divisible carton suitable for two-hand handling or suitable for single-hand handling when divided.

The chief object of the present invention is to form with a minimum of waste a divisible carton that can be handled as a unit or as two independent units.

Such a carton can be used for the retail sale of canned or bottled beer by the case or half case or by the wholesale trade for the sale of half or full cases of canned or bottled goods such as fruit juices, catsup, chili sauce, cocktail sauce, etc., for small stores and delicatessens.

The chief feature of the present invention resides in the formation of such a divisible carton from a single blank.

Other objects and features of the invention will be set forth more fully hereinafter.

The full nature of the invention will be understood from the accompanying drawings and the following description and claims:

In the drawings,

Fig. 1 is a developed plan of a single blank utilized in the formation of a divisible carton embodying the invention, the carton illustrated being of the longitudinally divisible type.

Fig. 2 is a transverse sectional view of such divisible carton with the covers and cover flaps in open position, the view being taken looking toward the united or union end of the case.

Fig. 3 is a longitudinal sectional view taken in the plane represented by line 3—3 of Fig. 2 and in the direction of the arrows.

Fig. 4 is a plan view of the box blank in knock-down ready for shipment.

Reference will first be had to Fig. 1 wherein the single blank is illustrated. The paper board utilized may be any type that can be creased and folded. Such material may be of a corrugated paper board stock character.

In Fig. 1, 10 indicates a half bottom, 11 an exterior side crease hinged thereto at 12, 13 a cover or half lid crease hinged to said side at 14. Crease hinged at 15 to the bottom 10 is an interior side and partition 16.

Hinged at 17 and 18 to side 11 are half ends 19 and 20 respectively. Hinged to the top of each at 21 and 22 are the top flaps 23 and 24 respectively. Hinged to the bottom of each at 25 and 26 are the bottom flaps 27 and 28 respectively. Hinged at 29 and 30 to the interior side 16 are the inner interlocking ends 31 and 32.

Ends 19 and 31, see Fig. 3, lap each other while ends 20 and 32 lap each other. The latter have hand holes 33 and 34 respectively. While the 35 and 28, respectively, and the half box is set up in

2

aforesaid describes one-half of the blank and the other half is similarly formed and similarly designated, it is to be noted, see Fig. 1, that adjacent ends 20 and 19 and adjacent cover flaps 24 and 23 are initially integral and have a hinge crease combined with a semi-perforated connection therebetween designated by numerals 35 and 36 respectively.

If desired, ends 19 and 31 may also be provided with hand holes. In that event there are two hand holes at each end of the case and either diagonal pair is usable for full case two-hand handling. When the blank, however, is developed as shown in Fig. 1 there is but one hand hole at each end of the case. When the two halves are erected as units and brought together in lapping relation, see Fig. 2, end 19 remote from junction 35 and end 20 also remote therefrom are substantially coplanar and a tape strip 37, readily severable by a pen knife or easily pulled therefrom, may be adhesively connected thereto and bridge the separation at the unconnected side edges of the inner walls 16 which then are disposed back to back in partition relation in the full case.

When complete division is required, the tape is severed or pulled off and the two half-case units opened slightly in Y relation. Then a pen knife can readily sever semi-perforated pre-formed junction 35—36 or the junction can be destroyed by pulling the two halves apart. When so severed each half case is a complete entity and will not open up if previously the top flaps 23 and 24 have been turned inwardly and down over the case and the half covers have been glued down as by the use of silicate of soda after the case has been filled. When so severed or separated into half units each can be picked up by the hand hole end and carried by one end.

Since it appears desirable to describe how the container or divisible case is erected, reference is now had to Figs. 2, 3 and 4 for an illustration of such condition. Now referring to Fig. 4, the folded taped blank is arranged in tubular formation with the cover and cover flaps down or in other words with the case inverted. Then flaps 27 and 28 of one half case are turned in and side partition 16 is turned in with end portions 31—32 lapping same. When portion 10 contacts or parallels inturned flaps 27 and 28, side partition 16 stands perpendicular to bottom 10. Then end portions 31—32, heretofore turned 180° for nesting, are turned back 90° to overlie flaps 27 and 28, respectively, and the half box is set up in

locked position. The other half is similarly erected. The box is then inverted.

The case is then filled, using separators if desired, and closed in the usual manner except that while herein the inside top flaps 23-24 are contiguous and joined to each other fold inwardly as a unit, and the similarly designated flaps which are remote therefrom each must be folded inwardly. The two half covers obviously fold inwardly to closing position as in a conventional sealed case. From an inspection of Fig. 1 it will be noted that the blank is substantially rectangular in outline and but little stock of that rectangle is not utilized.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. A one-piece divisible carton comprising a single blank having two halves integrally connected together for a portion of said halves and initially separable for the remaining portion of said halves, each half comprising integral, serially hinge connected half top, exterior side, bottom and interior partition-side portion, inner end flaps integral with and side edge connected to opposite side edges of the partition-side portion, exterior ends integral with and side edge connected to opposite side edges of the exterior side portion, cover flaps integral with and hinge connected to the top edges of each of said exterior ends, and bottom flaps integral with and hinge connected to the bottom edges of each of said exterior ends, said bottom flaps and inner end flaps being arranged, when in container formation, to lap each other and be transversely disposed for interlocking purposes.

2. A one-piece divisible carton comprising a single blank having two halves integrally connected together for a portion of said halves and initially separable for the remaining portion of said halves, each half comprising integral serially hinge connected half top, exterior side, bottom and interior partition-side portion, inner end flaps integral with and side edge connected to opposite side edges of the partition-side portion, exterior ends integral with and side edge connected to opposite side edges of the exterior side portion, cover flaps integral with and hinge connected to the top edges of each of said exterior ends, and bottom flaps integral with and hinge connected to the bottom edges of each of said exterior ends, the exterior end and the inner end flap at one side of each half of the carton having handholds formed therein which register when the carton is erected.

3. A one-piece divisible carton as set forth in claim 2 wherein the bottom flaps and inner end flaps, when in container formation, lap each other and are transversely disposed for self-locking purposes.

4. A one-piece divisible carton as set forth in claim 3 wherein an adhesive tape strip connects the two halves opposite the integral connection between said halves.

KENNETH C. FERGUSON.
